UNITED STATES PATENT OFFICE.

MARTIN A. FLANNERY, OF NEW YORK, N. Y., ASSIGNOR TO WILL & BAUMER CANDLE CO., INC., OF SYRACUSE, NEW YORK, A CORPORATION OF NEW YORK.

DESIGN FOR A VOTIVE STAND.

Application filed August 25, 1922. Serial No. 3,552. Term of patent 14 years.

To all whom it may concern:

Be it known that I, MARTIN A. FLANNERY, a citizen of the United States, residing at New York city, in the county of New York and State of New York, have invented a new, original, and ornamental Design for Votive Stands, of which the following is a specification, reference being had to the accompanying drawing, forming a part thereof.

In the drawing, the Figures 1 and 2 are respectively a front and side view of the votive stand constituting my new design.

I claim:

The ornamental design for a votive stand, substantially as shown.

In witness whereof, I have hereunto signed my name, at New York city, in the county and State of New York, this 4th day of August, 1922.

MARTIN A. FLANNERY.
